(57) **CLAIM**

An ornamental design for a wall hook, as shown and described.

DESCRIPTION

FIG. 1 illustrates a side view of the wall hook;
FIG. 2 illustrates the top view of the wall hook;
FIG. 3 illustrates the front view of the wall hook; and,
FIG. 4 illustrates a side view of the wall hook in an unclaimed environment of use taken from line 4-4 in FIG. 2.
The new wall hook is a novel design for a simple, yet elegant, modern industrial-type wall fixture for the storage of hanging items.
